United States Patent Office

Des. 197,224
Patented Dec. 31, 1963

197,224

VAN TYPE VEHICLE

David G. Peterson, 93 Van Cleve Way, Oakland, Calif.

Filed Nov. 23, 1962, Ser. No. 72,592

Term of patent 14 years

(Cl. D14—3)

F i g. 1

F i g. 2

FIGURE 1 is a perspective view of a van type vehicle as viewed from the left front thereof, showing my new design.

FIGURE 2 is a perspective view of the van type vehicle of FIGURE 1 viewed from the right rear thereof.

The dominant features of my design reside in the portions shown in full lines.

I claim:

The ornamental design for a van type vehicle, substantially as shown and described.
